(57) **CLAIM**

The ornamental design for a payment for a fuel dispenser, substantially as shown and described.

DESCRIPTION

FIG. 1 is a front, right side perspective view of a payment terminal for a fuel dispenser showing our new design;

FIG. 2 is a front view thereof;

FIG. 3 is a right side view thereof;

FIG. 4 is a left view thereof; and,

FIG. 5 is a top view thereof.

The bottom and rear of the payment terminal for a fuel dispenser of FIGS. 1-5 is devoid of surface ornamentation and is not part of the claimed design.

The portions of a payment terminal for fuel dispenser shown in broken lines form no part of the claimed design.

1 Claim, 5 Drawing Sheets
